UNITED STATES PATENT OFFICE

156,864

WASHBASIN AND DRESSING TABLE UNIT FOR BATHROOMS

William S. Brown, Rye, and Wayne A. Soverns,
Mount Vernon, N. Y., assignors to Thos. Emery's
Sons, Incorporated, Cincinnati, Ohio, a corporation of Ohio

Application June 26, 1948, Serial No. 147,216

Term of patent 14 years

(Cl. D4—2)

To all whom it may concern:

Be it known that we, William S. Brown and Wayne A. Soverns, both citizens of the United States and residing at Rye and Mount Vernon, respectively, in the county of Westchester and State of New York, have invented a new, original, and ornamental Design for a Washbasin and Dressing Table Unit for Bathrooms, of which the following is a specification, reference being had to the accompanying drawing, forming a part thereof.

Figure 1 is a perspective view of the washbasin and dressing table unit for bathrooms showing our new design.

We claim:

The ornamental design for a washbasin and dressing table unit for bathrooms, substantially as shown.

WILLIAM S. BROWN.
WAYNE A. SOVERNNS.
